UNITED STATES PATENT OFFICE.

ROBERT V. GALLAWAY, OF THORNTON, TEXAS.

DESIGN FOR A BED-SLAT HOLDER.

SPECIFICATION forming part of Design No. 33,335, dated October 9, 1900.

Application filed September 13, 1900. Serial No. 29,968. Term of patent 7 years.

To all whom it may concern:

Be it known that I, ROBERT V. GALLAWAY, a citizen of the United States, residing at Thornton, in the county of Limestone and State of Texas, have produced a new and original Design for a Bed-Slat Holder, of which the following is a specification.

The leading feature of this design consists in the design forming the subject-matter of the accompanying illustration, wherein the figure is a perspective view of a bed-slat holder embodying the new and original design.

The design is characterized by a concavo-convex horizontal member 1, having an up-standing conical projection 2 near the free

edge thereof and at the center. A back member 3 rises from the opposite portion of the member 1, in a plane at a right angle to the latter, and has a curved upper edge 4 and opposite circular openings 5 in the body thereof.

Having thus described the invention, what is claimed as new is—

The design for a bed-slat holder, herein shown and described.

In testimony that I claim the foregoing as my own I have hereto affixed my signature in the presence of two witnesses.

ROBERT V. GALLAWAY.

Witnesses:

E. B. CLAUNCH,
J. B. RASCO.
